US00D939954S

(12) United States Design Patent (10) Patent No.: US D939,954 S
(45) Date of Patent: * Jan. 4, 2022

(54) ABSORBENT ARTICLE PACKAGE

(71) Applicant: The Procter & Gamble Company,
Cincinnati, OH (US)

(72) Inventors: Jennifer L. Lowery, Blue Ash, OH
(US); Susannah L. Strydom,
Cincinnati, OH (US); Hector Ariza,
Chicago, IL (US); Jason Tyler,
Cincinnati, OH (US); Kyle A. Brown,
Cincinnati, OH (US)

(73) Assignee: The Procter & Gamble Company,
Cincinnati, OH (US)

() Term: 15 Years

(21) Appl. No.: 29/785,280

(22) Filed: May 25, 2021

Related U.S. Application Data

(62) Division of application No. 29/696,771, filed on Jul.
1, 2019, now Pat. No. Des. 923,470.
